CLAIM

The ornamental design for a tree cover, as shown and described.

DESCRIPTION

FIG. 1 is a perspective front view of a tree cover;

FIG. 2 shows a left side view thereof;

FIG. 3 shows a right side view thereof;

FIG. 4 shows a front side view thereof;

FIG. 5 shows a rear side view thereof;

FIG. 6 shows a top view thereof;

FIG. 7 shows a bottom view thereof; and,

FIG. 8 shows a perspective view thereof shown in an open position.

The broken lines represent portions of the tree cover which form no part of the claimed design. The circular broken lines in FIG. 8 as well as the stippled area inside of them represent portions of the tree cover which also form no part of the claim.
